UNITED STATES PATENT OFFICE.

RAPHAEL S. GREEN, OF CHICAGO, ILLINOIS.

BLADE-SHARPENING MACHINE.

No. 913,954.

Specification of Letters Patent.

Patented March 2, 1909.

Application filed December 14, 1908. Serial No. 467,571.

To all whom it may concern:

Be it known that I, RAPHAEL S. GREEN, a citizen of the United States, residing at Chicago, in the county of Cook and State of Illinois, have invented certain new and useful Improvements in Blade - Sharpening Machines, of which the following is a description, reference being had to the accompanying drawings, forming a part of this specification, in which corresponding characters of reference in the different figures indicate like parts.

The object of my invention is to provide a machine for sharpening razor and other analogous blades, which shall be so constructed that the blades may be automatically shifted from one side to the other at predetermined intervals, so that the two sides of the blade may be uniformly acted upon by the abrading or sharpening element.

A further object is to combine in a single machine two abrading disks, each arranged to rotate alternately in opposite directions, and preferably in opposite directions with respect to each other, the one to be used for honing and the other for stropping. Moreover, it is my purpose to so construct said machine that the alternate reversal of the disks may be discontinued at will and the disks caused to rotate continuously in one direction for any predetermined period; all of which is hereinafter more particularly described and definitely pointed out in the claims.

In the drawings, Figure 1 is a front elevation of a machine embodying the features of my invention, Fig. 2 is a plan view thereof, Fig. 3 is an enlarged view, partly in vertical section, showing the blade holder and means for reversing it, the section being taken longitudinally through said holder and through the driving gears for actuating it, Fig. 4 is a transverse vertical sectional view through said holder, Fig. 5 is an end view of the machine, and Fig. 6 is a transverse vertical sectional view taken upon the line 6—6, Fig. 1, viewed in the direction of the arrow there shown.

Referring to the drawings, 1 indicates a supporting base to which is bolted two upright standards 2, provided with bearings 3, in which is mounted a horizontal driving shaft 4, Figs. 1, 5 and 6, having beveled pinions 5 and 6 keyed to the opposite ends thereof, the former of which meshes into a like pinion 7 upon a vertical shaft 8, Figs. 1

and 3, while the latter meshes into a like gear 9 upon a corresponding vertical shaft, the upper ends of said shaft being supported in suitable bearings 10 and 11, respectively, while the lower ends rest in bearings 10^a 11^a upon the base, Figs. 1 and 5, formed in outwardly bent arms of the standards 2. Rigidly attached to the left hand shaft in said bearing 10 is a metal disk 12, Figs. 1 and 6, while a like disk 13 is secured in the same manner to the right hand shaft 8.

Supported upon the upper face of the disk 12 is a stone or abrading disk 14 of any suitable material adapted for honing purposes, and upon the disk 13 is secured a disk 15 of leather or other appropriate stropping material. Said disks are adapted to be rotated alternately in opposite directions by means of the following described mechanism: Mounted upon the main shaft 4, and secured thereto by means of a clutch 16^a for the purpose hereinafter stated, is a pinion 16, Figs. 1, 2 and 6, into which meshes the teeth of a segmental driving gear 17, the hub 18 of which is mounted upon a wrist-pin 19 supported by a lug 20 attached to the base-plate. An arm 21 is formed upon or rigidly attached to the hub 18 and is in turn, connected by means of a wrist-pin 22 to a pitman 23, the lower end of which is attached to a wrist-pin 24 upon a crank-arm 25 secured to the shaft 26 mounted in bearings upon the frame. A pulley 27, connected with any suitable source of power, serves to actuate the shaft 26 and in turn, to oscillate the segment 17. I prefer, in practice, to so proportion the segmental gear 17 and piston 16 with respect to each other, as to cause about six revolutions of the shaft 4 to each oscillation of the segment. Inasmuch as the bevelled gears which connect the shaft 4 with those which operate the disks are of equal size, it follows that each disk will be caused to alternately make six revolutions in one and six revolutions in another direction successively.

Having described the mechanism for actuating the disks, I will now describe the blade holders and the means for automatically reversing them to conform to the reverse movement of the disks.

The upper end of each of the disk supporting shafts is extended above the upper face of the disk, which it drives, and upon said extension is mounted a loose sleeve 28, Fig. 3, upon one side of which is a lug 29 having a horizontal radial bore adapted to re-

ceive the end of a short shaft 30 having a pinion 31 thereon. A polygonal recess is formed in said pinion for the reception of the polygonal end of a short detachable shaft 32, which is fitted into one end of the blade-holder 33. Said blade-holder consists of a hollow semi-cylindrical casing, shown in cross-section in Fig. 4 provided with a slot throughout its length into which the blade to be sharpened may be inserted by sliding it into said slot longitudinally. The back or thickened portion of the blade may be inserted within said cylindrical portion while the lips 34 which are by preference bent outwardly, as shown, bear with a spring pressure upon the body of the blade. A plug 35, Figs. 3 and 6, is removably inserted within the opposite end of the holder, said plug having a central bore therein for the reception of a bolt 36, adapted to be projected loosely into a bore 37, formed in the upturned end of a rigid arm 38, one of which is extended horizontally and forwardly from the parts 10 and 11 of the frame. A coiled spring 39, Fig. 3, is located in a longitudinal bore in the plug in which the bolt is inserted, while a pin 40 operating in a slot 41, serves to limit the outward movement of the bolt which forms the pivotal support for the end of the holder to which it is attached. When it becomes necessary to insert or remove a blade, the bolt is pushed back against the action of the spring 39 when the holder may be removed. The plug 35 is then withdrawn and the blade 42 inserted or removed from the part 33. Assuming it to be inserted, the plug 35 is then restored and the whole inserted in place in the machine as shown. Inasmuch as the sharpening disks are successively reversed, it follows that the holders must also be reversed in order that the blades may be maintained in proper relation thereto. For honing purposes the edge of the blade must always be opposed to the direction of the movement of the disk, or in other words, the disk must be moved toward said edge, while for stropping purposes, the opposite movement is necessary.

Extending outwardly and upwardly from the parts 10 and 11 in the same plane with the shaft 4, are arms 43 44, upon the ends of which are formed bearings 45 for the reception of the ends of a rock-shaft 46, to which is keyed two segmental gears 47, 48, respectively, adapted to mesh into teeth upon the upper faces of gears 49, 50 which gears likewise have teeth upon their lower faces adapted to engage the pinions 31 upon the blade-holders. Adjustably mounted upon the shaft 46 are collars 51, 52 provided with radially projecting pins 53, 54 arranged at an angle of about ninety degrees from each other which are intended to be alternately actuated for the purpose of rocking the shaft 46 and thereby reversing the blade-holders. Upon the shaft 4 are loosely mounted collars

57, 58, forming pivotal supports for levers, the long arms 59, 60 of which are extended upwardly and provided with laterally projecting pins 61, 62 in position, when said levers are vibrated to engage the pins 53, 54 and rock the shaft 46 back and forth. The short arms 63, 64 of said levers extend downwardly upon opposite sides of the segmental gear 17, upon which sides, respectively, are secured yielding latches 65, 66, mounted in bores formed in lugs 67 upon the faces of the segment as shown in Figs. 1, 2 and 6. Springs 68 serve to project said latches outwardly. The latches are so positioned upon the segment near its opposite edges, as indicated in Fig. 6, that they may be alternately brought into positive contact with the levers at the instant when the segment 17 is caused to reverse its movement. Each latch is provided with a comparatively long bevel 69 and a short bevel 70 upon its end, as shown in Fig. 6, said bevels being reversed with respect to each other as indicated, for the purpose hereinafter stated. The reversing levers 57, 58 are yielding held in the respective normal positions indicated in Fig. 6. Arms 71 are extended in opposite directions from the frame into the respective paths of the levers to form stops therefor while a spring 73, one end of which is connected to a pin 74 upon the lever and the other to one of said arms, serves to normally hold the levers respectively against said arms.

Having thus described the various parts of my improved device I will now explain its operation. Power being applied to the pulley 27 the segment gear 17 is caused to oscillate thereby rotating the shaft 4 in opposite directions with each reverse movement of said gear. This in turn causes the disks 12 and 13 to be rotated back and forth in like manner, but in opposite directions with respect to each other, as indicated by the arrows shown in Figs. 2 and 5. Owing, however, to the fact that the blades are required to be held differently with respect to the abrading surface, for honing than for stropping, it will be noted that the blades 42, in Figs. 1 and 2, are projected in the same direction and the gears which actuate them are arranged accordingly. The latches 65 and 66 are so adjusted with respect to the short arms 63, 64 of the levers that when the segment 17 shall have nearly finished its movement in a backward direction the long beveled surface of the latch 65 will be caused to engage the lower end of the lever arm 63, thereby pushing the latch back against its spring and permitting it to pass said arm at the instant when the segment shall have reached its extreme backward movement, it being understood that during said passage the lever is held in its normal position by means of the stop mechanism described. The latch 65 will then rest in the position indicated in

dotted lines in Fig. 6, and the reverse movement of the segment will cause the lever arm to be actuated by said latch. The pin 61 of the lever arm 59 being in engagement with the pin 53 upon the shaft 46 the latter is rocked thereby to the full limit of its movement. It should be borne in mind, however, that the relative movement of the segment 17 is much greater than that of the rock-shaft and hence provision should be made for disengaging the latch at the proper time. This is accomplished by means of the short bevel 70 thereon, which causes the latch to slip off from the end of the short arm 63 when the latter is moved to the proper angle. A like action occurs between the latch 66 and the arm 64, which results in reversing the movement of the rock-shaft. With each movement of the rock-shaft the blade-holders are reversed thereby shifting the respective blades so as to bring them in proper relation to the abrading surfaces of the reversible disks.

I do not wish to be confined strictly to the continuous reversing action of the disks for, as is well known to mechanics skilled in the art, it is sometimes necessary owing to variations in the temper or quality of the steel, for the operator to exercise his own judgment as to the manner in which he shall treat certain blades. In order to accomplish the desired results it may be necessary to rotate the sharpening disks continuously in one direction for a considerable time. For this reason I have provided means for throwing the reversing mechanism out of action and bringing a mechanism into action for rotating the disks continuously in one direction.

Mounted upon the shaft 4 is a normally loose pulley 75 adapted to be actuated by a small belt 76 running in a groove upon one edge of the pulley 27 adjacent to the main driving belt. The pulley 75 is adapted to be engaged by a clutch 77, which is connected with a clutch 16^a by means of a sleeve 78 having collars 79 thereon engaged by a shifting member, not shown, through which the two clutches may be actuated simultaneously so as to clutch the gear 16 and release the pulley or clutch the pulley and release the gear. Upon moving the clutch mechanism to the right the gear is released and the pulley caused to rotate, thereby running the disks continuously in one direction. During this time the blade-holders may be removed and the blade may be held by hand against the abrading surface until the desired result is accomplished when the holders may be reinserted, the clutches shifted and the regular automatic work continued. This feature is one of importance inasmuch as it enables the user to accomplish superior results in the delicate operation of finishing which might otherwise require a special machine.

From the foregoing it will be seen that the

operation of honing and stropping may be carried on upon the same machine simultaneously and that with speed, uniformity, and precision.

I do not wish to be confined to the exact construction shown, as it is obvious that it may be varied without departing from the principle involved.

In the example illustrated I have indicated a holder adapted to receive one of the various forms of safety razor blades. It is manifest, however, that the shape and size of the holder may be made to conform to the character of the blade to be sharpened.

Having thus described my invention, I so claim:

1. A machine of the class described, in which is combined a blade-sharpening disk, means for rotating the same, means for reversing the direction of rotation thereof, a blade-holder, and means for reversing the position thereof with each reverse movement of the disks.

2. A machine of the class described, comprising an abrading disk, an oscillating holder for holding a blade in position to be sharpened thereby, means for reversing the direction of rotation of said disk at predetermined intervals, and means, controlled by said disk reversing means, for positively oscillating said holder in harmony with the reversing movement of said disk.

3. A machine of the class described, comprising a plurality of abrading disks of varying fineness, an oscillating holder for holding a blade in operative proximity to each of said disks for sharpening the same, means for rotating said disks in opposite directions with respect to each other, means for automatically reversing the direction of movement of said disks at stated intervals, oscillatory blade-holders in operative connection with each of said disks, and means for oscillating said blade-holders, respectively, in harmony with each reversal of the disks.

4. A machine of the class described, in which is combined a blade-sharpening disk, an oscillatory segmental driving element for rotating the same in one direction and then in the other at predetermined intervals, an oscillatory blade-holder, and means interposed between said segmental driving element and said holder for shifting said blade-holder with each successive movement of said segmental driving element.

5. A machine of the class described, in which is combined a blade sharpening disk, an oscillatory element for reversing its direction of rotation at fixed intervals, a shifting blade-holder, and means in operative connection with said oscillatory element for shifting said blade-holder at the beginning of each reverse movement of said disk.

6. A machine of the class described, in which is combined a blade-sharpening disk,

means for rotating the same in opposite directions at predetermined intervals and means for throwing the reversing means out of action to cause said disk to rotate continuously in a given direction.

7. In a machine of the class described, the combination with abrading disks, a common shaft for actuating the same, two power-receiving elements mounted thereon, means for simultaneously locking one to and releasing the other from the shaft, a common source of power, means connected therewith for conveying power to one of said power-receiving elements first in one direction and

then in the other at predetermined intervals, 15 and means connected with said source of power for driving the other of said power-receiving elements continuously in one direction.

In testimony whereof, I have signed this 20 specification in the presence of two subscribing witnesses, this 11th day of December, 1908.

RAPHAEL S. GREEN.
